UNITED STATES PATENT OFFICE.

WILSON F. HUNT, OF WILLIAMSTOWN, MASSACHUSETTS.

HASP-LOCK.

No. 911,502

Specification of Letters Patent.

Patented Feb. 2, 1909.

Application filed May 13, 1908. Serial No. 432,636.

To all whom it may concern:

Be it known that I, WILSON F. HUNT, a citizen of the United States, residing at Williamstown, in the county of Berkshire 5 and State of Massachusetts, have invented new and useful Improvements in Hasp-Locks, of which the following is a specification.

This invention relates to hasp locks, the object in view being to provide means for locking a hasp without the aid of a key, doing away with the ordinary bolt and keeper and the expensive lock mechanism heretofore employed in locking various kinds 15 of doors.

With the above general object in view, the invention consists in the novel construction, combination and arrangement of parts herein fully described, illustrated and claimed.

20 In the accompanying drawings:—Figure 1 is a perspective view of the hasp lock showing portions of the door and door frame. Fig. 2 is a vertical section taken in line with the lock hook, the latter being 25 shown in elevation. Fig. 3 is an inner face view of the supporting plate showing the lock case in section.

Referring to the drawings, 1 designates an ordinary hasp provided with the usual 30 slot or aperture 2 adapted to slip over a staple 3 carried by a base plate 4, the hasp and plate being shown secured in the usual manner to a door and door frame sections of which are illustrated in Fig. 1.

35 In carrying out the present invention, I provide a lock hook 5, the shank of which extends upward and is pivotally mounted at 6 between outwardly projecting ears or lugs 7 on the plate 4. The plate is provided 40 with an opening 8 through which the nose 9 of the lock hook 5 passes said hook being shouldered at 10 to form a bearing therefor against the outer surface of the plate to limit the inward movement of the nose 9 of 45 the hook. When the hook is locked as shown in Figs. 1 and 2, the hasp 1 is held between the shank or body of the hook and the plate 4 and is thereby prevented from being withdrawn from the staple 3 in connection with which an additional padlock 50 may be used. 11 designates an ejector spring secured at one end to the plate 4 with the free end thereof acting against the nose or bill of the hook to force the same 55 outward when released.

Slidably mounted in a suitable guide casing 12 on the back of the plate 4 there is a bolt 13 which is movable into and out of engagement with a notch 14 in the hook as shown in Fig. 2, the bolt being normally held toward the hook by means of a spring 15 which is conveniently arranged in a longitudinal slot in the bolt as shown in Figs. 2 and 3.

16 designates a stop pin which lies within the slot of the bolt and is secured to the plate 4, said pin limiting the upward movement of the bolt and holding the same in position to be acted upon by the nose or bill of the hook which is beveled as shown at 17 so that in the act of pushing the hook inward, the nose or bill thereof acts to depress the bolt until the bolt snaps into engagement with the notch 14 thereby locking the hook. The plate 4 is also provided with a key-hole 18 for the reception of a suitable key 19, the bit 20 of which is movable into engagement with a shoulder on the bolt formed by notching the edge of the bolt as shown at 21. By turning the key in the proper direction the bolt is moved out of engagement with the hook and the latter is then thrust outward by the action of the ejector spring 11.

I claim:—

85 A hasp lock comprising in combination, a hasp, a base plate provided with an opening, a lock hook pivotally mounted on said plate, and movable in a plane perpendicular to the base plate and provided with a beveled nose insertible through the opening in the plate and formed with a notch, a shoulder on said hook adapted to bear against the surface of the plate to limit the inward movement of the hook, a key operated spring pressed bolt adapted to snap into engagement with the notch of the hook and to be deflected by the nose of the hook in the inward movement thereof, and a spring acting against the nose of the hook, substantially as and for the purpose specified.

90 95 100 In testimony whereof I affix my signature in presence of two witnesses.

WILSON F. HUNT.
